UNITED STATES PATENT OFFICE.

FREDERICK GEORGE SMITH, OF SARNIA, ONTARIO, CANADA.

SIGNALING INSTRUMENT.

1,324,525.

Specification of Letters Patent.

Patented Dec. 9, 1919.

Application filed July 12, 1918. Serial No. 244,618.

To all whom it may concern:

Be it known that I, FREDERICK G. SMITH, of the city of Sarnia, county of Lambton, Province of Ontario, Canada, have invented 5 certain new and useful Improvements in Signaling Instruments, of which the following is a specification.

This invention relates to electrical apparatus for teaching the signaling systems 10 commonly used commercially or in warfare, and my object is to devise apparatus which will give either visual signals, the tap signals of the Morse system, or the buzzing signals of the wireless apparatus. A further object is to arrange the apparatus so 15 that it may be used for the actual transmission of signals by Hertzian waves over limited distances, and also so that the taper or buzzer signals may be listened to telephonically.

My invention consists in the novel arrangement of the apparatus as illustrated in the accompanying drawing, which is a diagrammatical view of the apparatus.

25 In this drawing 1 is an electric circuit provided with a key 2, by means of which it may be closed or opened. Connected with this circuit is the circuit 3 of the lamp or visual signal device 4. 5 is the circuit of 30 the buzzer, of which 6 is the winding. The circuits 3 and 5 are each connected with the circuit 1 and with switch contacts 7 and 8. The buzzer is of ordinary construction, the circuit being ordinarily made or broken 35 between the vibrator 9 and the vibrator post 10. The vibrator will vibrate between the stops 11.

There is also provided by means of the wire 12 an electrical connection between the 40 winding 6 and a contact 13. By means of a switch 14 it is evident that either the visual signal device 4 or the buzzing device 5 may be brought into the circuit with the key 2, so that by the operations of the key 45 either visible signals may be given or the buzzer operated to give the signals commonly used in wireless telegraphy. A mirror 28 is preferably provided so that the light from the lamp may be sent in any direction.

50 When, however, the switch 14 is engaged with the contact 13, the vibrator no longer forms part of the circuit of the buzzer and the latter will operate to give single taps 55 only such as commonly employed in Morse signaling.

In order that signals may be heard by telephone, I provide the buzzer with a secondary winding 15, which secondary winding is connected with the terminals 16 and 17 to which a telephone circuit 18 may be connected. As it is desirable to be able to vary the intensity of the signals in the telephone circuit, I connect one end of the secondary winding by means of the wire 19 65 to the terminal 17 and tap the winding at different points in its length by means of the wires 20 and provide a switch 21 by means of which any one of the wires 20 may be connected with the terminal 16. 70

It is also desirable to arrange the device to act as a sender of wireless signals and I therefore connect a terminal 22 with the vibrator post 10. This may be conveniently done by connecting the post by means of 75 the wire 23 with the circuit 12. To the terminal 24 is connected a wire 25 connected with the buzzer winding 6. The terminal 22 is intended for connection with an aerial 26, while the terminal 24 is connected with 80 the ground 27 when aerial signals are to be sent.

It will be understood, of course, that the parts of the apparatus may be constructed of any well known devices, and the secondary winding 15 may be readily altered to any 85 buzzer of ordinary type.

From the above description it will be seen that I have devised signaling apparatus which will satisfactorily carry out the objects of my invention as set out in the preamble of this specification.

What I claim as my invention is:—

1. In signaling apparatus, the combination of an electric circuit; a key for making and 95 breaking said circuit; a visual signal device; a buzzer device; a switch and connections whereby the key controlled circuit may be completed at will either through the visual signal device, through the vibrator of the buzzer, or direct through the coil of the buzzer; a terminal for an aerial connected with the vibrator post; and a terminal for a ground connection connected 100 to the winding of the buzzer coil. 105

2. In signaling apparatus, the combination of an electric circuit; a key for making and breaking said circuit; a visual signal device; a buzzer device, a switch and connections whereby the key controlled circuit may be completed at will either through 110 the visual signal device, through the vibra-

- tor of the buzzer, or direct through the coil of the buzzer; a secondary winding on the buzzer coil; and terminals for telephone connections connected with said secondary winding.
5. In signaling apparatus, the combination of an electric circuit; a key for making and breaking said circuit; a visual signal device; a buzzer device; a switch and connections whereby the key controlled circuit may be completed at will either through the visual signal device, through the vibrator of the buzzer, or direct through the coil of the buzzer; a secondary winding on the 10 buzzer coil; terminals for telephone connections connected with said secondary winding; and means for cutting out more or less of the secondary winding from the telephone circuit.
15. In signaling apparatus, the combination of an electric circuit; a key for making and breaking said circuit; a visual signal device; a buzzer device; a switch and connections whereby either the key controlled circuit may be completed at will either through the visual signal device, through the vibrator of the buzzer, or direct through the coil of the buzzer; a terminal for an aerial connected with the vibrator; a terminal for a ground connection con-
- nected to the winding of the buzzer coil; a secondary winding on the buzzer coil; and terminals for telephone connections connected with said secondary winding.
35. In signaling apparatus, the combination of an electric circuit; a key for making and breaking said circuit; a visual signal device; buzzer and tapper mechanism and connections therefor; means for bringing either the visual signal device, the buzzer 40 connections or the tapper connections into the key controlled circuit; an aerial connected with the vibrator post; and a ground connection connected to the winding of the 45 buzzer coil.
6. In signaling apparatus, the combination of an electric circuit; a key for making and breaking said circuit; a visual signal device; buzzer and tapper mechanism and connections therefor; means for bringing either the visual signal device, the buzzer 50 connections or the tapper connections into the key controlled circuit; a secondary winding on the buzzer coil; and terminals for telephone connections connected with 55 said secondary winding.

Signed at Sarnia, Ontario, this 25th day of June, 1918.

FREDERICK GEORGE SMITH.
